UNITED STATES PATENT OFFICE.

CHARLES HENRY SCHMIDT, OF WINCHESTER, TEXAS.

STAPLE-SETTING IMPLEMENT.

SPECIFICATION forming part of Letters Patent No. 629,473, dated July 25, 1899.

Application filed May 13, 1898. Serial No. 680,612. (No model.)

To all whom it may concern:

Be it known that I, CHARLES HENRY SCHMIDT, a citizen of the United States, residing in Winchester, county of Fayette, State of Texas, have invented certain new and useful Improvements in Staple-Setting Implements; and I do hereby declare the following to be a full, clear, and exact description of the invention, such as will enable others skilled in the art to which it appertains to make and use the same.

The invention has for its particular object to provide a simple and effective hand instrument or tool for uniting together by small metallic staples pieces of leather, canvas, or other fabric, and the implement is especially useful in making and mending harness, belting, shoes, &c.

Generally speaking, the invention consists of a pair of nipper or tong like jaws, one of which is provided with an anvil against which a plunger mounted in the other jaw forces the ends of a staple, causing the staple ends to turn inwardly toward each other and clench themselves after passing through the material being operated upon. This kind of instrument is not broadly new; but my improvement embodies novel features of construction which enable the staples to be driven at any desired angle without changing the angle of the jaws to the work.

In some kinds of saddlery-work, and especially in making and mending shoes, it is very desirable to put the staples in line with the seams, so as to imitate a line of stitches, and as the seams are often angular and crooked it is necessary to constantly change the angle of the tool to the work; but this cannot always be done when working in corners and on the interior of hollow articles, such as boots and shoes, and I propose making the staple-carrier and anvil (one or both) adjustable in the jaws of the implement, so as to drive and clench the staples in any line desired, and, specifically, my invention consists in the means whereby I do this.

I have illustrated one form of my invention in the accompanying drawings, wherein—

Figure 1 is an elevation of the entire device. Figs. 2 and 3 are face views of the staple-carrier and anvil, respectively; and Fig. 4 is a sectional view of both jaws, show-

ing in further detail the manner of mounting and adjusting the plunger and anvil, and the views in Fig. 5 show a modification.

55

In the drawings the same letters of reference denote like parts in all the views.

A' denote the jaws of the implement, which are pivoted together at *a* in the usual manner and are provided with handles B B', as usual. The jaw A is the one carrying the staple-holder and the plunger for driving the staples through the work, and the jaw A' is the one carrying the anvil, against which the ends of the staple strike and which acts to 65 turn them inwardly and clench them.

The staple-holder is denoted by the letter C, and consists of a block having a pair of jaws *c c*, projecting toward the jaw of the instrument which carries the anvil. The staple-holder is arranged to slide in the plunger of the instrument, so that it may recede into the same as the plunger is pressed against the anvil, the rear part of the plunger being cut out for this purpose, as shown at *d* in Fig. 4. Projecting rearwardly the staple-holder C has a 70 stem or heel extension *e*, which passes out through a perforation *p* in the jaw A in line with the jaws *c c* of the holder C, and on the outer side of the plunger-carrying jaw A of 75 the instrument itself there is a spring *s*, riveted so that its free end bears against the heel extension and keeps the staple-carrying jaws *c c* normally projected beyond the end of the plunger and yet allows them to withdraw or recede into the plunger when the latter is pressed against the anvil.

80 The plunger or staple-driver is denoted by D. It is cored out, as shown at *d*, for a purpose heretofore explained, and carries the 85 staple-holder C, as also previously described. This plunger is mounted in its carrying-jaw A, so as to be adjusted into various positions and so, also, as to be removable. The means here shown for so mounting it (though the 90 invention is not limited to these particular means) consist of two springs *ff*, riveted or otherwise secured, as illustrated in Fig. 4, to opposite sides of the plunger-carrying jaw A and extending toward the anvil in the opposite jaw A' parallel with each other in the plane the plunger is intended to have. The plunger is cylindrical in general outline, but has its exterior provided with a plurality of 95 100

flat surfaces *i*. In the present drawings the surface of the plunger is octagonal; but the invention is not limited to the number of angular surfaces, but only that they should be polygonal. As will be seen from the drawings, particularly Figs. 2 and 4, the springs *f f* lie upon opposite sides of the plunger and inclose it throughout its length, bearing each on one of the flat faces of the plunger-body. At 10 their outer ends the springs *f f* have inturned points *h h*, which stand in toward each other and overlap the front end of the plunger. These points serve to prevent any accidental displacement of the plunger endwise, and the 15 springs bearing on its flat exterior surfaces on opposite sides serve to hold it against accidental rotation at the same time. The springs permit the plunger to be adjusted around its longitudinal axis into as many positions as 20 there are flat surfaces on its exterior, and the points *h h*, being only spring-held in place, permit its ready removal. In order to seat the plunger firmly in its carrying-jaw *A*, the end of the latter is cut away, as shown at *t t*, 25 so as to form a shoulder to back and hold the same.

As will be understood from Figs. 2 and 4, the staple-carrying jaws stand on opposite sides of the longitudinal center of the plunger, and the carrier is so mounted in the 30 plunger that though it can slide in it it cannot turn except the plunger itself turns. In all the figures of the drawings the staple-carrying jaws are shown as standing in line 35 with the handles of the instrument. In this position the direction of the staples would of course always be in line with the handles; but, as before stated, when working in corners or on the interior of hollow articles—such 40 as boots, shoes, &c.—it is frequently impossible to hold the handles at the angle required in order to place the rivets in line with one another, and it is here that my invention finds its principal advantage, for, as will be 45 readily understood from the drawings, it is only necessary to rotate the plunger and staple-holder and set it at whatever angle may be desired when the work may proceed, and it is to be particularly noted that in doing 50 this it is unnecessary to remove either the staple, the plunger, or the staple-holder.

Referring now to the anvil-carrying jaw *A'*, (best illustrated in Figs. 3 and 4,) *E* denotes the anvil. All instruments of this character 55 require an anvil of some sort, and my improvement in respect to this feature consists in making it revolvably adjustable on its seat and in the particular construction of the anvil and seat. The anvil itself consists of a 60 block of metal having a rearwardly-projecting tang that enters a depression or perforation in the jaw *A'* behind the seat proper. The anvil is revolvably secured in or upon its seat in any preferred way, friction being relied on in the form shown in the drawings. In 65 order to provide the seat for the anvil, the end of the jaw *A'* is cut away, so as to leave

a ledge *e'* and a shoulder or abutment *f'*, and the ledge is provided on its upper surface with polygonal faces *e'*, as clearly shown in 70 Fig. 3. The periphery of the head or body part of the anvil *E* is also provided with a plurality of angular or flat faces to correspond with those of the seat *e'*. The object of this construction of the anvil and its seat is to provide for the before-described revolvble adjustment of the anvil to correspond with the similar adjustment of the staple-carrier and plunger. The anvil is firmly held from rotation by the side faces of the seat, and in 80 order to adjust it it is only necessary to partially remove it with the thumb and forefinger, turn it to the required angle, and reinsert it.

Such being the construction of my improved 85 implement, no explanation of its operation seems necessary further than is clearly indicated in the above description. It is to be understood, however, that the adjustable feature of the anvil is not necessary to the successful working of the adjustable staple-carrier. As shown herein, the anvil is provided with two little depressions *g g*, which are curved or cam-shaped on the bottom and into which the free ends of the staple enter and 90 are deflected inward toward each other. When such depressions are employed, it will probably be necessary to make the anvil adjustable; but should these depressions be omitted or modified in form or arrangement 95 it would be unnecessary to have the anvil rotatable.

The arrangement shown in Fig. 5 is slightly different from that of the other figures in that the angular faces of the anvil are provided 105 with depressions *u*, and the arm *A'* has a spring-pressed pin *r*, adapted to engage the depressions and hold the anvil in any position. The pin *r* has a small thumb-screw *x* projecting through a slot outwardly, by means 110 of which the pin may be withdrawn to permit the anvil to be rotated. In this arrangement the tang of the anvil passes clear through the end of the arm *A'* and has a head *o*, and the anvil is freely rotatable without removal 115 and does not rely on the angular faces of the seat for holding it in place, as in Fig. 3, there being enough clearance to permit it to turn.

Having thus described the invention, what I claim is—

1. In a staple-setting tool, the combination with the jaws of the implement, of a revolvably-adjustable plunger having a polygonal exterior surface and mounted in a yielding bearing or support, a staple-carrier mounted 125 in said plunger, and a polygonal seat in the plunger-carrying jaw on or in which said plunger may be adjusted.

2. The combination with pivoted jaws, of a rotary adjustable plunger mounted in one of 130 said jaws, a staple-carrier mounted to slide in said plunger, and provided with a heel projection extending through the jaw, a flat spring bearing against said projection, a ro-

tary adjustable anvil carried by the other jaw, and a yielding device for locking said anvil against rotation.

3. In a staple-setting tool, the combination with the plunger D, having a polygonal exterior surface of the plunger-carrying jaw having the springs f, f, inclosing the plunger on opposite sides and forming a releasable seat for the same, said springs having the inturned edges h, h, to hold the plunger to its seat.

4. In a staple-setting tool, the combination

with the plunger-carrying jaw, of a removable plunger, and springs f, f, inclosing the plunger on opposite sides, and having in-turned ends h, h.

In testimony whereof I affix my signature in presence of two witnesses.

CHARLES HENRY SCHMIDT.
